US0D1016565S

(12) **United States Design Patent** (10) **Patent No.:** **US D1,016,565 S**
(45) **Date of Patent:** **** Mar. 5, 2024**

(54) **CHILDREN'S SILICONE CUP**

(71) Applicant: **Guang Hu**, Shenzhen (CN)

(72) Inventor: **Guang Hu**, Shenzhen (CN)

(73) Assignee: **Guang Hu**, Shenzhen (CN)

(**) Term: **15 Years**

(21) Appl. No.: **29/853,526**

(22) Filed: **Sep. 16, 2022**

(51) **LOC (14) Cl.** **07-01**

(52) **U.S. Cl.**

USPC **D7/578**; D7/533; D7/510

(58) **Field of Classification Search**

(57) **CLAIM**

The ornamental design for a children's silicone cup, as shown and described.

DESCRIPTION

is a top perspective view of a children's silicone cup, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions the children's silicone cup, which form no part of the claimed design.

1 Claim, 8 Drawing Sheets
